UNITED STATES PATENT OFFICE.

WILLIAM M. SMITH, OF MERIDEN, CONNECTICUT, ASSIGNOR TO THE
MERIDEN BRITANNIA COMPANY, OF SAME PLACE.

DESIGN FOR A COFFIN-HANDLE SOCKET.

SPECIFICATION forming part of Design No. 12,122, dated January 11, 1881.

Application filed December 7, 1880. Term of patent 14 years.

To all whom it may concern:

Be it known that I, Wm. M. SMITH, of Meriden, in the county of New Haven and State of Connecticut, have invented a new Design 5 for Coffin-Handle Socket; and I do hereby declare the following, when taken in connection with the accompanying drawing and the letters of reference marked thereon, to be a full, clear, and exact description of the same, 10 and which said drawing constitutes part of this specification, and represents a face view. This invention relates to a design for socket by which to attach the lifting-handle to coffins and like purposes; and the design consists in 15 the configuration as shown in the accompanying illustration.

The socket represents a sash or ribbon as hanging over the end of the handle-levers A, drooping in the center between the levers, and

hanging down at the outside at each end. The 20 pivots of the levers extend beneath the central portion of the ribbon, as indicated in broken lines; but the construction is no part of the design. The space above the drooped portion in the center is filled with a floriated ornamentation, B, all as shown in the accompanying illustration.

I claim—

The design for coffin-handle socket, consisting of the representation of a ribbon hanging 30 over the handle-levers, drooping between them and the ends down upon the outside, as shown in the accompanying illustration.

WILLIAM M. SMITH.
